(57) **CLAIM**

The ornamental design for a nozzle for helium balloon kit, as shown and described.

DESCRIPTION

FIG. 1 is a perspective view of a nozzle for helium balloon kit showing my new design;

FIG. 2 is a front view thereof;

FIG. 3 is a side view thereof;

FIG. 4 is an opposite side view thereof;

FIG. 5 is a top view thereof; and,

FIG. 6 is a bottom view thereof.

In FIG. 1, the broken lines showing of environmental structure for purposes of illustrating the nozzle for helium balloon kit in a condition of use. The broken lines and the structure they depict form no part of the claimed design.

1 Claim, 3 Drawing Sheets
